SAMUEL HOCH AND DEBORAH HOCH, OF NEW YORK, N. Y.

MEDICO-THERAPEUTIC AND DIAGNOSTIC APPARATUS.

Application filed December 19, 1924. Serial No. 756,922.

The present invention relates to improvements in medico-therapeutic and diagnostic apparatus for types known as intestinal irrigators for use in baths for subaqueous applications.

Among the several objects of the apparatus is the provision of a rectal tube, accessible from the rear of the patient, which will permit of a natural and comfortable sitting position conducive to defecation, the device supporting the rectal tube being flexibly and self conformably mounted to prevent pressure on the walls of the intestines.

Another feature is to provide a seat or saddle having binding means which prevent the entrance of fecal matter into the vagina of females, if used by them, the saddle and binders being easily and thoroughly sterilized as is customary and necessary.

A further aim is to produce a device in which strict isolation of the inflowing medicated liquor and the outflowing septic contents of the intestines is maintained and the medicated water in the bath used to increase the therapeutic action of the treatment.

A still further object is to provide a hygienic and sanitary receptacle for the excreta, air and water tight, and easily sterilizable, the same containing a strainer to separate the solid from the liquid parts, enabling the former to be preserved for chemical, biological and bacteriological analysis.

These, and other objects and advantages of the invention, which will become more fully known as the description proceeds, are secured by the novel construction, combination and arrangement of parts herein-after described and shown in the annexed drawing, forming a material part of this disclosure, and in which:—

Fig. 1 is a longitudinal sectional view of a bath tub equipped with an irrigating device constructed in accordance with the invention and illustrating its application.

Fig. 2 is a top plan view of the saddle and binder used in connection therewith, drawn to an enlarged scale.

Fig. 3 is a side elevation view of the same.

Fig. 4 is an enlarged fragmentary sectional view taken on line 4—4 of Fig. 2.

Fig. 5 is a sectional detail view taken through the regulating means, substantially on line 5—5 of Fig. 3.

The bath tub, designated generally by the

numeral 10 in the drawing, is shown as having a raised bottom portion to provide a seat, and may be filled with water or medicated liquid to a level indicated at 11.

The apparatus consists of a hollow body 12, having a saddle shaped upper surface 14 provided with a front extension 15 and a corresponding rear extension 16, these extensions being so shaped as to conform to the buttocks of a patient, and a pair of divergent binders 17 at the front and a single like element 18 at the rear are capable of being brought into intimate relation with the body, to which they may be secured by any convenient means, a binder 17' having a single forwardly extending element being provided for females, by which the vagina is protected.

Extending from the front of the element 12 is a tubular projection 19 engageable with a flexible conduit 20 communicating with a sectional globular receptacle 21 disposed near the foot of the tub.

The lower section of receptacle 21 is shown as resting upon a seat 22 secured to the bottom of the tub and provided with an outlet pipe 23 communicating with a drain, however, this receptacle may be positioned at any height found to be most convenient.

Within the receptacle is a finely meshed sieve like container 24 to separate the solid fecal matter from the liquid, and is provided with a handle 25 extending out through the line of juncture of the sections, shown here as at the median line of the receptacle, this container being readily removable at will, to permit examination of the matter therein or rotatable to dump the contents as preferred.

A rectal tube or irrigator nozzle 26 having a rounded end provided with perforations 27 is supported on the end of a tube 28, bent at a right angle, its horizontal portion extending outwardly through a recess 29 in the rear wall of the hollow body 12, to engage axially in the bulbous forward end 30 of a housing 31, containing a bored chamber 32.

A plunger 33 is loosely fitted to the bore and provided with an extending knurled operating head 34, the plunger having an annular recess in which is fitted a packing ring 35, and said plunger is further provided with an extension 36 adapted to abut the inner end of the bore, thus limiting its inner movement.

The rear end of the tube 28 is screw-threaded into the inner end of the plunger, as at 37, and provided with holes 38 in communication with the chamber 32.

5 In order to maintain a liquid tight joint between the walls of the recess 29 and end 30 of the housing, a rubber nipple or packing 39 is interposed and held in close engagement by a flat spring 40 attached to the rear wall of the hollow body 12 and bent to project over the outer end of the housing, the spring being forked at 41 to straddle the plunger 33 which extends through it.

15 A pair of nipples 42 and 43 are fixed in the housing 31 to communicate with the chamber or bore 32, one of these nipples 42 having engaged upon it a flexible tube 44 leading to a reservoir, not shown, containing a supply of medicated liquid and the other 20 nipple 43 is connected with a similar flexible tube 45 entering the upper member of the receptacle 21, for the transmission of gases, and any surplus of medicinal liquid.

25 The operation of the apparatus is quite evident as illustrated in Fig. 1, which shows the device placed in a tub, the rectal tube inserted, from the rear, into the body when in a comfortable posture, and it will be noted that the mounting of the tube permits the 30 body to sway limitedly sidewise or move to the rear, the plunger 33 moving outwardly to accommodate such movement.

35 The supply tube 44 will be supplied with a valve, not shown, to control the inlet of liquid, while the tube 45 is provided with a spring clamp for constricting or effectively closing its bore while the supply tube is in use. Should, however, an overpressure be indicated by the manometer, (not shown) 40 then the supply is shut off and the spring clamp released to permit patient to be relieved of overpressure by allowing the liquid in the intestines to be drained off into the receptacle 21. To hasten the relief from the 45 overpressure, the supply tube is disconnected from its valve and instead, attached to the nipple 46, thus providing a double discharge from the patient.

50 It will be readily understood that this apparatus can be manipulated by skilled experts only as its operation by laymen, untrained physicians or nurses might prove dangerous.

55 It is to be understood that the rectal tube 26 is guided by hand from the back of the patient, to point rearwardly, avoiding excessive contact with the walls of the rectum and pressure upon hemorrhoids, which usually exist in cases where there is constipation, and where the use of the apparatus is 60 beneficial, which in the hands of an expert and experienced physician, is not only of therapeutic value, but a material aid in diagnosis.

65 It is also to be noted that the medicated water in the tub will support and increase the therapeutic action of the treatment by stimulating elimination through the skin and resorption of the ingredients.

70 The foregoing disclosure is to be regarded as descriptive and illustrative only, and not as restrictive or limitive of the invention, of which obviously an embodiment may be constructed including many modifications 75 without departing from the general scope herein indicated and denoted in the appended claims.

76 Having thus described our invention, what we claim as new and desire to secure by Letters Patent, is: —

1. An intestinal irrigating apparatus for use in a bath tub, comprising a saddle shaped seat, binders on said seat, to contact with the person subjected to treatment, a rectal tube extending upward from said seat, said tube having a rearward extension, a housing, a plunger in said housing into which said extension is engaged, means for preventing leakage between said housing and said seat, said means being limitedly angularly displaceable and capable of rotation, means to maintain said housing in intimate contact with said seat, means to conduct fluids into said housing, and means to carry away a surplus of liquid and gases 90 from said housing.

95 2. An intestinal irrigating apparatus for use in bath tubs, comprising a hollow saddle shaped seat having a recess in its rear wall, a housing having a bulbous point engaging in the recess, means for pressing the housing towards the recess, a packing intermediate the recess and housing point, a plunger movable in said housing, means 100 limiting the entry of said plunger, a rectal tube fixed at one end in said plunger and extending upward through said seat, means for conveying liquid to the space in said housing to communicate with said tube, and means for removing excess liquid from said 105 housing.

110 3. An intestinal irrigating apparatus for use in bath tubs, comprising a hollow saddle shaped seat having a recess in its rear wall, a housing pivotally mounted in the recess, a spring pressing the housing to its seat in the recess, a plunger movable in the housing, a rectal tube extending upward through said seat, a right angled rearward extension on said tube, said extension being fixed in said 115 plunger angularly and rotatably movable therewith, and means for the inlet and outlet of fluids to said housing and tube.

120 Signed at New York, in the county of New York and State of New York, this 9th day of December 1924.

SAMUEL HOCH.
DEBORAH HOCH.
